UNITED STATES PATENT OFFICE.

WILLIAM C. FOX, DECEASED, LATE OF SAN FRANCISCO, CALIFORNIA, BY LEWIS J. FOX, ADMINISTRATOR, OF SAN FRANCISCO, CALIFORNIA.

GOLD-SAVING DEVICE.

1,092,524.

Specification of Letters Patent.

Patented Apr. 7, 1914.

Application filed January 29, 1913. Serial No. 744,997.

To all whom it may concern:

Be it known that WILLIAM C. Fox, deceased, late a citizen of the United States and resident of San Francisco, in the county 5 of San Francisco and State of California, did invent new and useful Improvements in Gold-Saving Devices, of which the following is a specification.

His invention relates to an improved apparatus for saving fine gold, the object of 10 my invention being to provide an apparatus of this character which will be very effective for this purpose.

In the accompanying drawing, Figure 1 15 is a broken side view of his apparatus, Fig. 2 is a broken plan view thereof.

His improved apparatus is made of precisely the same uniform sections, any number of which, as may be found desirable, are 20 connected together in longitudinal series.

Referring to the drawing, 1 indicates the bottom of a section of his improved apparatus which, in general, resembles a sluice box. To said bottom are attached side walls 25 2, and all the sections, when connected together, are confined between the main side walls 3. To the bottom of the lower end of each section is secured a wooden bar 4 to which is fastened, as shown at 6, the upper 30 end of a casting, the lower end of which is formed with a tongue 8, which is inserted between the upper end of the bottom of the next lower section, and a bracket 9 riveted to the under side of said bottom and spaced 35 therefrom. Said casting is formed on its upper side with two approximately semi-circular cavities, an upper smaller cavity 11, and a lower cavity 12 of considerably greater width and depth. Fitting within 40 these cavities is a thin plate or lining 13 of silver. The upper end of this plate is bent downward and contained between the casting 7 and the bar 4, and the lower end is bent forward to form a lip 14. This plate is 45 held in position in the cavities by means of vertical end plates 16, the lower edges of which are conformed to fit against said plates in said cavities, said end plates being riveted, as shown at 17, to the sides of the casting. A wearing plate 18 is bolted to the 50 casting, its upper edge projecting over the rear wall of the lower cavity 12. Both of these cavities are filled to a sufficient height with quicksilver.

The upper edge of the plate 18 is slightly 55 higher than the lower edge of the bottom 1 next above it. By reason of this construction, and also by the employment of two cavities or riffles, one immediately behind the other, two distinct currents are produced, so 60 that the water has at each riffle an eddying downward direction, compelling all material held in suspension to take a similar course, and causing an agitation of said material sufficient to precipitate any gold held in 65 suspension, and to cause it to come in contact with the quicksilver in the bottom of the riffles, the larger riffle principally, and amalgamate with the same, or, if the gold be rusty to cause it to sink to the bottom of said 70 riffle. The pulp is held in loose suspension upon the quicksilver and black sands are kept constantly moving thereon, so that the fine and flake gold sinks therethrough. After passing over each pair of riffles, the 75 gold is able to settle to the bottom of the pulp in passing over the smooth bottom below the same, before arriving at the next pair of riffles.

I claim:

1. A riffle unit consisting of a smaller concave riffle, a larger concave riffle immediately below, and a substantially smooth bottom immediately above, the first-named riffle, and a sheet of amalgamable material 85 lining both of said riffles and having its rear edge bent forward.

2. A riffle unit consisting of a smaller concave riffle, a larger concave riffle immediately below, and a substantially smooth 90 bottom immediately above, the first-named riffle, a sheet of amalgamable material lining both of said riffles, and a lip extending forwardly from the upper end of said bottom and adapted to overlie the larger riffle 95 of another unit.

3. A riffle unit consisting of a smaller concave riffle, a larger concave riffle immedi-

ately below, and a substantially smooth bottom immediately above, the first-named rifle, a sheet of amalgamable material lining both of said rifles and having its rear edge bent forwardly, and a lip extending forwardly from the upper end of said bottom and adapted to overlie the larger rifle of another unit.

In testimony whereof I have hereunto set

my hand in the presence of two subscribing ¹⁰ witnesses.

LEWIS J. FOX,
Administrator of the estate of said William C. Fox, deceased.

Witnesses:

F. M. WRIGHT,
D. B. RICHARDS.
